PRINTING PLATE CLAMP

Howard M. Barber, Pawcatuck, Conn., assignor to
C. B. Cottrell & Sons Company, Westerly, R. I.,
a corporation of Delaware

Original application October 2, 1942, Serial No.
460,501. Divided and this application June 12,
1943, Serial No. 490,563

2 Claims. (Cl. 101—387)

In the use of printing plate clamps of the type where a screw is employed for clamping the cylinder and nut to the plate support, as, for instance, a cylinder, in their plate clamping position along a groove in the cylinder, it has been found that at high speeds it is difficult to maintain these clamps in their operative positions due to the strain of holding the plates on the cylinder at said high speeds. It has also been found that the clamps not only break due to the excessive strain thereon under high speeds but that they also break due to the fact that the clamp screws receive directly the shocks of the blows delivered by the pressmen against the nuts to force the clamps along the grooves into their plate clamping positions, thus causing a shearing strain on the clamp screws.

The object of my invention is to provide means for relieving this shearing or side strain on the clamp screws when forcing the clamps into their operative position, and thus make it possible to successfully use this type of clamp in high speed presses; said strain on the screws being eliminated by the provision of coacting surfaces of various forms between the plate hooks and nuts, for absorbing the blows on the nuts and thus preventing the effect of the blows being transferred to the clamp screws.

Practical embodiments of my invention are represented on an enlarged scale in the accompanying drawing in which

Fig. 1 represents a detail side view of a grooved cylinder with one form of printing plate clamp engaging one curved side edge of the printing plate;

Fig. 2 represents a section taken in the plane of the line II—II of Fig. 1;

Fig. 3 represents a section taken in the plane of the line III—III of Fig. 2;

Fig. 4 represents an end view of the plate clamp nut;

Fig. 5 represents a bottom plan view of the plate clamp hook;

Fig. 6 represents an end view of the hook; and

Fig. 7 represents a side view of the hook.

Fig. 8 represents a section similar to Fig. 3, showing a second form of clamp;

Fig. 9 represents a side view of the nut;

Fig. 10 represents an end view of the same;

Fig. 11 represents a bottom plan view of the hook;

Fig. 12 represents an end view of the same; and

Fig. 13 represents a side view of the hook.

The printing plate support which is herein shown as a cylinder, is denoted by 1, and one of

its usual spiral grooves by 2, which groove may be of any well known or approved cross sectional shape.

The curved printing plate is denoted by 3 and its curved beveled edge by 4.

The plate clamp comprises the nut 6, the plate hook 7 and the clamp screw 8. In the embodiment shown in Figs. 1 to 9 inclusive the plate hook 7 is shown as provided with a guide member 9 which is provided with parallel side edges 10, 10, slidably engaging the side walls of the groove 2 and thus forming an extended bearing for guiding the plate hook 7 along the groove with the nut 6, into and out of engagement with the beveled edge 4 of the printing plate 3. It will be noted that the guide member 9 projects under the beveled edge of the plate and forms together with the beveled edge of the plate hook an angular recess for receiving the beveled edge 20 of the plate, thereby permitting the hook from riding up thereon.

It will be understood that the clamp screw 8 passes freely through the plate hook 7 and its guide member 9 into threaded engagement with the nut 6.

This nut 6 in both of the embodiments illustrated is shown as having a shallow recess 11 adapted to receive the guide member 9 of the plate hook when the parts of the clamp are 30 assembled.

Coacting surfaces are provided on the plate hook guide member 9 and the nut 6 for preventing the plate hook from exerting a side strain on the clamp screw 8 when endwise force such 35 as repeated blows is directed against the clamp nut 6 to drive the clamp along the cylinder groove into engagement with the beveled edge 4 of the printing plate 3.

In the embodiment shown in Figs. 1 to 7 inclusive the uprising inner wall of the shallow recess 11 in the nut 6 which houses the guide member 9 of the plate hook 7 is shaped to form two angular surfaces 12, 13 which coact with corresponding angular surfaces 14, 15 of the 40 adjacent end wall of the said guide member; the coacting surfaces 12 and 14 being parallel with the back edge of the plate hook and the coacting surfaces 13 and 15 being at right angles to the cylinder groove 2.

In the embodiment shown in Figs. 8 to 13 inclusive the uprising inner wall of the shallow recess 11 in the nut 6 forms a diagonal surface 16 which coacts with a corresponding diagonal surface 10* at one end of the hook guide member 9.

In both of the embodiments the coacting surfaces of the plate hook and nut are so located that they, rather than the clamp screws, will receive the force of any blows against the nuts for driving the clamps into their engagement with the printing plates.

While I have shown the printing plate clamps as mounted on a cylindrical support it is obvious that these clamps could readily be adapted without invention for use on flat supports.

This application is a division of my copending application filed October 2, 1942, Serial No. 460,501.

It is evident that various changes may be resorted to in the construction, form and arrangement of the several parts without departing from the spirit and scope of my invention, and hence I do not intend to be limited to the particular embodiments herein shown and described, but

What I claim is:

1. In a plate clamp adapted to be moved along a grooved support into engagement with an edge of a printing plate, a hook provided with a guide member slidable in a groove of said support, a

nut having a shallow recess for housing the guide member, and a clamp screw passing freely through the hook and guide member into threaded engagement with the nut, said guide member having a diagonal surface and said nut having a corresponding coacting diagonal surface for preventing the hook from exerting side strain on the screw when the nut is subjected to endwise force.

2. In a plate clamp adapted to be moved along a grooved support into engagement with an edge of a printing plate, a hook provided with a guide member slidable in a groove of said support, a nut having a shallow recess for housing the guide member, and a clamp screw passing freely through the hook and guide member into threaded engagement with the nut, said guide member having angular surfaces and said recess having corresponding coacting angular surfaces for preventing the hook from exerting side strain on the screw when the nut is subjected to endwise force.

HOWARD M. BARBER.
